UNITED STATES PATENT OFFICE.

MAX FEHRINGER, OF NEW YORK, N. Y.

PAPER, FABRIC, OR THE LIKE, NOT SENSITIVE TO ACIDS OR ALKALIS.

1,233,334.

Specification of Letters Patent. Patented July 17, 1917.

No Drawing. Application filed March 1, 1915, Serial No. 11,344. Renewed December 12, 1916. Serial No. 136,543.

To all whom it may concern:

Be it known that I, MAX FEHRINGER, a subject of the German Emperor, at present residing in New York, in the county of New York and State of New York, have invented a new and useful Paper, Fabric, or the like, Not Sensitive to Acids or Alkalies, of which the following is a specification.

There are only very few acid- and alkali-proof materials of which the solutions can be used for impregnating or coating paper, fabrics and the like to give the latter the same qualities.

Some of these materials are again too expensive for general use, or not odorless, or one cannot mix and suspend sensitive colors in the solutions of the same.

According to the present invention the solutions of the cheap artificial cumaron-rosin are especially suitable for imparting to paper, fabrics and the like resistance to influences of acids or alkalies.

This material is a polymerid of coumarone and indene obtained from the coaltar-fractioin boiling between 160-190°. It is a solid of light yellow color with a glassy fracture and differs in its chemical structure and especially in the physical distinctions of solubility very much from the ordinary rosin and similar materials. These are wholly or partially soluble in alcohol and alkali. The cumaron-rosin is soluble in neither alcohol nor alkali and for this last reason very well qualified to make the paper, etc., alkali-proof.

This is of great value for papers, etc., to be used for wrapping soaps or other chemical products, whose ingredients would otherwise destroy the paper or the colors of the same.

The novel solution of cumaron-rosin can be made advantageously by dissolving the

pulverized material in benzin, gasolene or other suitable petroleum products, benzol or its homologues, chlorethylene, or mixtures of all of them; it is a transparent and very adhesive liquid.

One may add if necessary in small portions emollients such as castor-oil or the like.

If one is compelled to deodorize the cumaron rosin one may wash the pulverized material at first with alcohol, then dry and finally dissolve it as described before.

The coating or impregnation of the paper, fabric and the like can be done on one side or on both sides, either by hand or suitable machinery for coating rollpaper and the like. The following drying process is preferably carried out with heat.

A preference of the so manufactured goods is, that they can be made very inexpensively. As they are further odorless, water- and grease-proof they are suitable for every use.

For some purposes the surface of the paper, fabric and the like may be treated at first with liquids of glue or albumin or the like, dried and then dressed or coated with the cumaron-rosin solution. The latter is also a good binding substance for colors and by coating the paper, fabrics, or the like with a colored cumaron-rosin solution it is possible to produce very good effects, as characterized by a fine glossy luster.

What I claim as my invention and desire to secure by Letters Patent is:

Paper, fabric, or the like resistant to acids and alkalies, coated or impregnated with cumaron-rosin.

MAX FEHRINGER.

Witnesses:

MAX ARTHUR BAUM,
WILLIAM CHRISTIE.
